E. BARTHOLOMEW.

APPARATUS FOR OBTAINING THE PRODUCTS OF PEAT.

APPLICATION FILED SEPT. 10, 1914.

1,175,919.

Patented Mar. 21, 1916.

UNITED STATES PATENT OFFICE.

ELLIS BARTHOLOMEW, OF TOLEDO, OHIO, ASSIGNOR TO THE NATIONAL PEAT REFINING COMPANY, OF CLEVELAND, OHIO, A CORPORATION OF DELAWARE.

APPARATUS FOR OBTAINING THE PRODUCTS OF PEAT.

1,175,919.

Specification of Letters Patent. Patented Mar. 21, 1916.

Original application filed December 22, 1913, Serial No. 808,213. Divided and this application filed September 10, 1914. Serial No. 861,081.

To all whom it may concern:

Be it known that I, ELLIS BARTHOLOMEW, a citizen of the United States, and a resident of Toledo, in the county of Lucas and State of Ohio, have invented a certain new and useful Apparatus for Obtaining the Products of Peat; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to apparatus for extracting the commercial byproducts contained in peat.

It consists in providing a means for evaporating and purifying certain hydrocarbons such as are derived from peat.

The apparatus usable in the conduct of the process may be of different forms and still such modifications may contain my invention.

In order to show that the invention is practical, I have selected an apparatus embodying my invention as an illustration and shall describe the apparatus hereinafter. The apparatus selected is illustrated in the drawings, in which,—

Figure 1 is a conventional diagrammatic illustration of the system for obtaining the by-products of peat in which the device embodying my invention is connected. Fig. 2 is a sectional view of the purifier shown in Fig. 1. Fig. 3 illustrates a sectional view of the purifier showing the electric heater.

Referring to Fig. 1, 1 is a large container or bin, suitably supported, for containing peat. The peat is placed in the container or bin 1 through the hopper 2 located in the top of the bin. The opening in the hopper 2 is appropriately sealed by a cover plate 3. The bin 1 is provided with a connector 4 to direct the peat into the separator 5.

The top 6 of the separator 5 is provided with a petcock 7 to allow escape of gases or air, as may be desired. The lower end of the shell 5 is hopper-shaped and directs the peat upon an electric heater 8 of the form

shown in Fig. 3, which illustrates the heater used in the purifier shown in Fig. 2. The separator may also be provided with a stirrer of any suitable form which is operated by a pulley wheel 9 to work the peat down to the heater 8 as shown and more particularly described in my co-pending application Serial No. 808,213, filed December 22, 1913.

A connecting pipe or conveyer 11 is located below the electric heater and as the peat is turned into coke by the intense heat of the heater 8, the coke is conducted to the bin 12.

As the peat falls upon the electric heater the gases and liquids are heated and pass from the separator. The coke, which is formed by the heat produced by the heater 8 passes to the bottom of the separator and to the bin 12. The coke may be removed from the bin 12 through an opening 13 located at the bottom of the bin. A plate 14 seals the opening 13.

The gases separated from the peat together with any moisture that may exist therein are driven off and are directed into a collector 20, through the pipe 24 wherein the heavy liquids such as tar, are collected. They immediately condense upon entering the collector 20 and fall to the bottom of the collector. The gases and lighter liquids together with water vapor, if water is contained in the peat, pass out through the upper end of the collector. The lower end of the collector 20 is provided with a plug 21 or other suitable opening, which will permit the removal of liquids and cleaning of the collector. The upper end is provided with a cap or plug 22. Pet-cocks 23 may be provided for removing liquids and gases, as may be desired.

The collector 20 is connected with a condenser 30 by means of a pipe 25. The condenser 30 separates the liquids from the vapors coming from the collector. They are received through the inlet port 31 located in the bottom of the condenser. The lower end 32 of the condenser is dome-shaped and collects the liquids which are condensed in the condenser by means of cool water which is supplied and conveyed away through

suitable pipes. The condenser 30 also operates to separate the gases from the lighter liquids. The vapors are condensed by the cooling effect of the cold water and collected in the dome 32 of the condenser. The liquids pass out through the outlets, one located in the dome and the other located in the cover which closes the top of the condenser. The bottom is provided with a suitable cap or plug 37, which may be opened and permit the cleaning of the dome of the condenser. The plug is provided with a pet-cock 29 for allowing residue liquids to pass out.

15 The liquids from the condenser 30 pass to a purifier 38. The purifier is a double flask-shaped receptacle having heaters 39 and 40, one located in the lower part of the purifier, and the other located above the constricted portion of the purifier. The two parts are connected together by a coupler 41 having right and left handed threads. The liquids enter the upper part of the purifier through the inlet 42 and pass down 25 through the purifier and by the heater 39 and through the connector 41 to the heater 40 located at the bottom of the purifier.

The liquid is heated to a temperature which will cause the evaporation of one of 30 the many liquid elements contained in the bottom of the purifier. This temperature will vary according to the boiling point of the liquid to be separated. The vapor produced passes up from the purifier into the upper part of the purifier and past the upper heater 39. To separate the different elements of the liquid contained in the purifier, the heat produced by the heater 40 may be raised step by step to the boiling points 40 of the liquid elements contained in the purifier. As this temperature is altered the liquids will be driven off. A plurality of condensers may be suitably connected to the top of the purifier and condense the vapors 45 of the liquid elements which may be driven off from the purifier. The liquid when heated by the heater 40 on account of the presence of alkalies and other earth compounds in solution derived from the peat 50 produces foam which sometimes reaches the upper end of the lower part of the purifier and near to the heater 39. The temperature of the heater 39 keeps the heat in that part of the purifier up to about 300° Fahrenheit. The heat causes the reduction of the foam and keeps the foam in the lower part of the purifier. It also superheats the gases, and vapors arising from the lower part of the purifier. Suitable thermometers 55 are located in the vicinity of the heaters 39 and 40 in order that the temperature of the heaters may be suitably regulated. Insulated connectors 44 make connection with the heaters whereby a source of current having a high amperage may be con-

nected with the heaters. The connectors are insulated from the body of the purifier by means of fiber plates 45.

The purifier 38 is provided with plugs 75 and 76 for cleaning the interior of the purifier. The vapors produced by the heat of the heater 40 and superheated by the heater 39 pass out through the top 46 of the purifier and the pipe 48 to a condenser 50. A pressure gage 47 may be connected to the plug 46 located in the upper end of the purifier and a condenser 50 of any suitable form where the vapors and gases are cooled by water supplied and conveyed away by suitable pipes.

The condenser 50 is provided with a coil 51, which is connected to the pipe 48. The vapor enters the interior of the coil at one end and passes out through the other end. The condenser is connected to a suitable reservoir 55 for storing the liquid produced by the condensation of the vapor in the condenser 50. The liquid may then be drawn off for consumption.

The gases which are non-condensable at the pressure and temperature produced in the condenser 30, are directed to a scrubber 56 of a suitable form where the ammonia gas is separated from the hydro-carbon gases. The gases enter the inlet 57 located near the bottom of the scrubber. The scrubber is partly filled with water. The level of the water is detected or shown by the water-gage 58. The water-gage is provided with the usual valves 59. The gases pass up through the water in the manner well known in the art, the ammonia enters into solution with the water while the hydro-carbon gas passes out through the outlet 61. The lower end of the scrubber is provided with a plug or cap 62, which may be opened for cleaning the interior of the scrubber. A cock 63 is located in the plug 62 for permitting the removal of the water or solution contained in the scrubber, and other material that may collect therein. The scrubber is connected to a suitable reservoir 65 for storing the hydro-carbon gas from whence the gas may be drawn as desired.

In order to obtain a suitable balancing pressure and in order to fill the system with a gas similar in character to that produced by the heater 8 in the separator 5 and to drive all air out of the system, the reservoir 65 is connected to the bin 1 by means of a pipe 66 which is provided with a valve 67 and a check-valve 68. The valve 68 prevents automatically any return of gas or mixture of gas and air to the reservoir 65 from the bin 1 which might be formed in the filling of the bin 1.

The heaters 8, 29 and 40 are connected to the source 10 of current by means of the conductors 70 which is shown diagrammatically in Fig. 1.

The pipes are provided with suitable valves and the condensers are connected to a source of water supply and a drain or other suitable outlet.

Having thus described my invention, what I claim as new, and desire to secure by Letters Patent, is,

A purifier for purifying the products of peat having lobe-shaped portions located one above the other and communicating

with each other and electrically heated rods located above and at the lower end of each of said portions.

In testimony whereof, I have hereunto signed my name to this specification in the presence of two subscribing witnesses.

ELLIS BARTHOLOMEW.
